UNITED STATES PATENT OFFICE.

OTTO GEISLER, OF CHICAGO, ILLINOIS.

TENSION MEANS FOR DRUMHEADS.

Application filed October 8, 1924. Serial No. 742,462.

My invention relates to improvements in tension means for drum heads, and it consists in the combinations, constructions and arrangements herein described and claimed.

An object of my invention is to provide a tension means for drum heads in which the tension of the batter head and the snare head may be adjusted independently of one another. This is especially necessary when the batter and snare heads are of unequal thickness or strength. In the ordinary type of drum, it is a common experience to find that the batter head has caused an unnatural stretching of the snare head, due to the fact that the tension means for the batter and snare heads have common connecting elements.

A further object of my invention is to provide a device of the character described by means of which either the batter or snare heads may be adjusted or removed without in any way affecting the tension of the remaining head in place upon the shell.

A further object of my invention is to provide a device of the character described in which that area encompassing the mid portion of the circumferential outer surface of the shell is entirely unobstructed, thereby presenting not only a pleasing appearance, but providing a smooth surface which in the larger types of drums are apt to bear upon the uniform or coat of the person supporting the drum.

A further object of my invention is to provide a device of the character described which is extremely rigid, due to the fact that a portion of the tension device is fashioned integral with the shell of the drum, and all possibility of movement relative to the shell thereby precluded.

A further object of my invention is to provide a device of the type described that is simple in construction, that may be easily operated, that holds its adjustment with a high degree of efficiency, and which is thoroughly practical for the purpose intended.

Other objects and advantages will appear in the following specification, and the novel features of the invention will be particularly pointed out in the appended claim.

My invention is illustrated in the accompanying drawings forming part of this application, in which—

Figure 1 is a sectional view through a

drum equipped with my improved tension means.

Figure 2 is an enlarged sectional view transverse to the section shown in Figure 1.

Figure 3 is a fragmentary sectional view of a modified form of my invention.

Figure 4 is a fragmentary sectional view of another modified form of my invention.

Figure 5 is a view along the line 5—5 of Figure 4, and

Figure 6 is a fragmentary sectional view of a further modification of my invention.

In carrying out my invention I make use of a metal annular drum shell 1. I prefer to construct this shell of aluminum or other alloy which is rigid and light in weight. The shell 1 is provided with the ordinary type of batter head 2 and snare head 3, preferably of a high quality of calf.

The heads 2 and 3 are held in place upon the shell 1 by means of hoops 4 and 5 having outwardly extending radial flanges 6 and 7, respectively, at the inner ends thereof. A plurality of tension members 8 are projected through suitable openings provided through the flanges 6 and 7. These tension members 8 have hook members 9 at the innermost ends thereof, and are threaded on the opposite ends 10, (see Figure 2). Threaded adjusting nuts 11 are disposed upon the threaded portions 10 of the members 8 on the outermost sides of the flanges 6 and 7.

A pair of spaced apart, annular, radially extending, parallel flanges 12 are carried integral with the shell, and extend from the outer surface thereof at equal distances from the mid point of the shell. These flanges are L-shaped in cross section and are disposed with one side 13 parallel with the outer side wall of the shell and with that side perpendicular to the shell disposed toward the hoops 4 and 5, respectively. The radially extending parallel flanges 12 are formed integral with the drum shell 1 as shown in Figure 2. The entire shell with the lugs 12 is manufactured by the die-casting process.

The hook portions 9 of the members 8 are fashioned to engage with the flanges 12 and to partially overlie the portions 13 of the flanges (see Figure 2).

From the foregoing description of the various parts of the device, the operation

thereof may be readily understood. In adjusting the heads in a drum equipped with my improved tension means the batter head and the snare head are first adjusted to a point as near as possible to the proper tension. This is done by turning the threaded adjusting nuts 11, thus drawing the hoops 4 and 5 respectively toward the mid point of the shell 1 and stretching the heads. In the ordinary type of drum when the batter head or the snare head is adjusted, the remaining head is necessarily stretched or loosened either way depending upon the adjustment applied to the head in question. It is readily apparent therefore that there is a constant tendency to equalize tension of the two heads in the ordinary type of drum. Assuming, for the moment, that these heads are of the same strength and thickness it is still necessary that the batter head be adjusted with greater tension than the snare head. This is due to the fact that some of the force imparted to the batter head is lost in transmission from that head to the snare head of the drum. For this reason the batter head is usually given a little more tension than the snare head in order to transmit the stroke in full and still retain sufficient force to properly rebound the sticks.

30 However, in the present day type of drum, the batter head is constructed of tougher, heavier material than the snare head, thus making it absolutely essential for efficient operation to have the adjustment tension of the two heads entirely separate, and accomplished by suitable means. This I have accomplished in the provision of the tension means described in the foregoing pages.

40 Another very important advantage attained is that either head may be removed and replaced without in any way altering the adjustment of that head remaining upon the shell.

45 In Figure 3 I have shown a modified form of my invention in which I employ a single flange to take the place of the pair of radially extending flanges 12 shown at 14. This flange 14 is substantially T-shaped in cross section, thus permitting the hook portions 9 of the members 8 to be engaged with the flanges from either side. This construction of course necessitates the use of members 8

which are slightly longer than the type shown in Figure 2, but the operation in adjusting the heads is precisely the same. 55 This construction is especially advantageous in narrow shells.

In Figures 4 and 5 I have shown a further modification of my invention in which I eliminate the annular flanges 12 and supply therefor radially extending lugs 15 substantially L-shaped in cross section (see Figure 4) with which the hook members 9 of the members 8 are permitted to engage in the manner shown in Figure 4. This modification of my invention is especially useful when extreme lightness in the shell is desired. In Figure 6 I have shown still a further modification of my invention in which I employ radially extending lugs 16 70 having bores 17 therethrough parallel with the outer surface and axis of the shell 1. This form of my invention is employed with a tension member which does not contain the hook portion 9, but instead an enlarged head portion 18 for eliminating the movement of the lug through the flanges 6.

With reference to Figures 3 and 4 of the drawings, it will be noted that the flange 14 and the lugs 15 are formed integral with the shell 1. In this form of the invention the flange and lugs are cast with the shell by a die-casting process.

I claim:

A drum comprising a shell having outwardly extending annular flanges, the flanges having outer portions bent at right angles and extending toward each other, thereby providing grooves facing one another, a batter head covering one end of said shell and a snare head covering the other end of said shell, hoops binding said heads to said shell, said hoops having outwardly extending flanges with openings therein, tension members disposed in said openings and having hook-shaped portions receivable in said grooves and bearing against the walls of said shell flanges, said hook-shaped portions being spaced from each other, and means carried by said tension members and disposed opposite to said hoop portions for moving the hoops toward each other for increasing the tension upon said heads.

OTTO GEISLER.
